Geo. P. Kimmel

UNITED STATES PATENT OFFICE

HARRY WILKING, OF DECATUR, ILLINOIS

WIRE TWISTING DEVICE

Application filed June 18, 1930. Serial No. 462,030.

This invention relates to a wire twisting device particularly adapted for use in tightening wires extending across forms for concrete work, and the invention has for its primary object to provide, in a manner as hereinafter set forth, a wire twisting device by means of which a comparatively inaccessible pair of wires may be quickly and conveniently twisted to tighten the same.

With the foregoing and other objects in view, the invention consists of the novel construction, combination and arrangement of parts as hereinafter more particularly described, and as illustrated in the accompanying drawings wherein is shown an embodiment of the invention, but it is to be understood that the description and drawings are to be taken as illustrative and that the invention is intended to be limited only by the scope of the claims hereunto appended.

In the accompanying drawings in which like numerals are employed to designate like parts throughout the several views:—

Figure 1 is an elevation of a wire twisting device in accordance with this invention.

Figure 2 is an enlarged fragmentary section taken at a point indicated by the line 2—2 of Figure 1.

Figure 3 is a fragmentary section taken at a point indicated by the line 3—3 of Figure 2.

Referring to the drawings in detail, the numerals 1 and 2 indicate a pair of handle members, the handle member 1 having an end portion 3 outwardly offset with respect to the handle member 2 in order that the outer end portions of the handle members may be positioned a substantial distance apart with the inner end portions thereof positioned comparatively close together and in parallel relation. The outer ends of the handle members are formed with enlarged socket forming members 4 for the reception therein of extensions 5 in order that the length of the handle members may be increased as desired.

At the inner end thereof, the handle member 1 is formed with a substantially disk-shaped head 6 formed with a concentrically arranged opening 7. Diametrically opposite the handle portion 1, the head 6 is formed with a tapered recess 8 extending through the

wall of the opening 7. The handle member 2 is provided at its inner end with a head 9 which is similar in every respect to the head 6.

The heads 6 and 9 are rotatably mounted upon a pair of annular shoulders 10 formed exteriorly of a mutilated ratchet 11. The shoulders 10 extend through the concentrically disposed openings in the heads 6 and 9 and the heads are maintained in position on the shoulders by means of a pair of side plates 12 which are fixedly secured to the ratchet to form parts thereof by suitable bolts 13 extending through the plates 12 and into the shoulders 10 and ratchet 11. The ratchet 11 and plates 12 are formed in their peripheral faces with a recess 14 which extends inwardly beyond the axis of the ratchet and plates. The recess 14 is adapted to be aligned with the recesses 8 and when so aligned, the side walls of the recess 14 are flush with the side walls of the recesses 8. Having one end secured to the plate 12 which retains the head 9 is a pin 15 which projects into the recess 14 midway between the side walls of the latter.

On opposite sides of the recess 8, the head 6 is provided on its inner face with a pair of pawls 16 and 17 for engagement with the teeth 18 on the peripheral face of the ratchet 11. Each of the pawls is preferably formed of relatively stiff, resilient material, and is rigidly secured to the head 6 in a manner to have its inner end forced against the periphery of the ratchet 11. The head 9 is provided on its inner face with a pair of pawls 19 and 20 similar to the pawls 16 and 17.

In the operation of the device, the ratchet 11 is rotated in a manner to position the recess 14 in alignment with the recesses 8 in order that a pair of wires, such as 21, may be received through the recesses with the pin 15 extending between the wires. One of the handle members is then reciprocated while the other handle member is held stationary in order that the pin 15 may be rotated with respect to the wires to twist the latter. For example, the handle member 2 is held stationary while the handle member 1 is reciprocated which causes the pawls 16 and 17 to rotate the ratchet 11 in a clock-wise direction as viewed

in Figure 2. During the movement of the handle member 1 in a direction to cause the ratchet 11 to be rotated by the pawls 16 and 17, the ratchet is rotated relative to the head 9 on the handle member 2. During movement of the handle member 1 in the opposite direction, the ratchet is held stationary by the pawls 19 and 20, and the head 6 and handle 1 are rotated relative to the ratchet. When the recess 14 is brought into alignment with the pawls 17 and 20, the ratchet 11 is controlled solely through the pawls 16 and 19. When the recess 14 is brought into alignment with the pawls 16 and 19, the ratchet 11 is controlled solely through the pawls 17 and 20. Owing to the constant engagement of at least one of the pawls on the stationary handle member with the teeth 18, there can be no return movement of the ratchet 11 when the reciprocating handle member is moved relative thereto.

It is thought that the many advantages of a wire twisting device in accordance with this invention will be readily apparent, and although the preferred embodiment of the invention is as illustrated and described, it is to be understood that changes in the size, shape and arrangement of parts may be resorted to, so long as such changes fall within the scope of the invention as defined in the appended claims.

What I claim is:—

1. A wire twisting device comprising, a rotatable ratchet formed in its periphery with a recess extending inwardly beyond the axis of the ratchet, a pin secured to the ratchet and extending into the recess midway between the side walls of the latter, a pair of handle members rotatably mounted on the ratchet, and a pair of pawls carried by each handle member for engagement with the ratchet on opposite sides of said recess.

2. A wire twisting device comprising, a rotatable ratchet formed in its periphery with a recess extending inwardly beyond the axis of the ratchet, a pin secured to the ratchet and extending into the recess midway between the side walls of the latter; a pair of oppositely disposed, annular shoulders formed on said ratchet, a pair of handle members having their inner ends formed with substantially disk-shaped heads rotatably mounted on said shoulders, each of said heads being formed in its periphery with a recess corresponding in width to the recess in the ratchet, and a pair of pawls carried by each head for engagement with the ratchet on opposite sides of the recess therein.

3. A wire twisting device comprising, a rotatable ratchet formed with a pair of oppositely disposed, annular shoulders, a pair of handle members having their inner ends formed with substantially disk-shaped heads rotatably mounted on said shoulders, each of said heads being formed in its periphery with

a recess, a pair of plates fixedly secured to said shoulders for maintaining the heads in position thereon, said ratchet and plates being formed in their peripheries with a recess adapted to be aligned with the recesses in said heads and extending beyond the axis of the ratchet and plates, a pin secured to one of said plates and extending into the recess therein midway between the side walls of such recess, a pair of pawls carried by each head for engagement with the ratchet on opposite sides of the recess therein, and a removable extension for each of said handle members.

4. A wire twisting device comprising, a pair of reciprocable handle members, a rotatable ratchet disposed between the inner ends of the handle members, said ratchet having its peripheral face formed with a recess extending inwardly beyond the axis of the ratchet for the reception therein of a pair of wires to be twisted, a pin secured to the ratchet and projecting into the recess for disposition between the wires therein, and a pair of pawls carried by each of said handle members for engagement with the ratchet on opposite sides of said recess.

In testimony whereof, I affix my signature hereto.

HARRY WILKING.
